UNITED STATES PATENT OFFICE

EDMUND HOFFMAN, OF BROOKLYN, NEW YORK, ASSIGNOR TO AMERICAN CAN COMPANY, OF NEW YORK, N. Y., A CORPORATION OF NEW JERSEY

DESIGN FOR A POWDER CAN

Application filed July 23, 1928. Serial No. 27,563. Term of patent 14 years.

To all whom it may concern:

Be it known that I, EDMUND HOFFMAN, a citizen of the United States, residing at 558 Argyle Road, Brooklyn, county of Kings, and State of New York, have invented a new, original, and ornamental Design for a Powder Can, of which the following is a specification, reference being had to the accompanying drawing, forming a part thereof.

On the drawing:

The figure is a perspective view of a powder can, showing my new design.

I claim:

The ornamental design for a powder can as shown.

EDMUND HOFFMAN,
